VACUUM BREAKER VALVE

Modesto Callejo, Bronx, N. Y., assignor to Bidoro Manufacturing Co., Inc., Mount Vernon, N. Y., a corporation of New York

Application September 28, 1938; Serial No. 232,047

2 Claims. (Cl. 251—118)

This invention relates to improvements in valves and has particular reference to a vacuum breaker valve especially adapted for use in water distribution systems.

An object of the invention is to provide an improved valve of simple, practical and economical construction which will effectively prevent syphoning of water from a fixture in a distribution system into the main supply line thereof when a vacuum occurs therein.

Another object is to provide a vacuum breaker with a sliding valve operable in a sleeve bearing formed in one section of the structure and extending into another section thereof, said valve being equipped with means to divert any sediment in the supply line, to which the structure is connected, from the space between said valve and its bearing so as to prevent entry of said sediment into said space, and thereby to insure effective and positive operation of said valve.

The above and other objects will appear more clearly from the following detailed description when taken in connection with the accompanying drawing which illustrates a preferred embodiment of the inventive idea.

In the drawing:

Figure 1 is a diagrammatic view, partly in section, of a portion of a water distribution system including a number of fixtures of various types and in association with some of which is illustrated vacuum breakers embodying features of the present invention.

Figure 2 is a vertical sectional view through one form of a vacuum breaker valve showing the sliding valve thereof in the position it assumes when water in the distribution system is flowing through the structure.

Figure 3 is a view similar to Figure 2 showing the position of the valve when the inlet of the structure is closed.

Figure 4 is a transverse section on the line 4—4 of Figure 3.

Figure 5 is a similar view on the line 5—5 of Figure 3.

In Figure 1 of the drawing there is partially illustrated a water distribution system in which a plurality of fixtures, such as a drinking fountain 12, basin 13, toilet 14, and bathtub 15, are located on different floors of a building. The water supply for these various fixtures is conveyed thereto through a main riser pipe 16 connected to a suitable source (not shown) from which the water supply is controlled by a master valve 17. The supply for the lower fixtures 12 and 13 is conveyed thereto through a valve con-

trolled pipe 18 in the customary manner. For the fixtures 14 and 15, there are provided branch pipes 19 and 20, respectively, with standard control valves 21 and 22 for governing the flow from the riser 16 to said fixtures. In the use of fixtures such as shown at 14 and 15, there is a possibility of waste water being syphoned therefrom into the riser 16 when a temporary vacuum occurs in the latter, with the result that such waste water may be subsequently conveyed to other fixtures in the system. In order to avoid this contingency, a vacuum breaker valve structure is interposed between each of the fixtures 14 and 15 and the control valves therefor, the construction of said vacuum breaker being such that when the valve thereof is operated by pressure of water in the riser 16 a free flow of the supply to the fixture will be had. However, when said supply is shut off, or a vacuum occurs in the riser, said sliding valve will operate to close communication between the fixtures and the riser so as to eliminate any possibility of waste water in the fixtures being syphoned back into the riser. Said vacuum breaker structure is also utilized to control the admission of air into the riser and thus aid in breaking any temporary vacuum in the latter. For this purpose each of the vacuum breaker structures, shown in Figure 1, has connected thereto at one end an air intake pipe 23 the other end of which is joined to a vertical drain pipe 24. The upper end of the latter pipe extends above the topmost fixture in the system and is open to the atmosphere while the lower end of said pipe may be disposed below a drain 25. The pipes 23 also act as an overflow for any water which may pass the vacuum breaker structure without flowing into the fixture and such overflow will be conveyed through said pipes 23 into the drain pipe 24.

The vacuum breaker is shown as comprising a body consisting of separable sections, generally indicated at 26 and 27, connected by the screw threads 28 formed interiorly of the section 26 and on the extension 29 of the section 27. The section 26 is reduced at its lower end and exteriorly screw threaded for coupling to the control valve 21 as illustrated in connection with the fixture 14, or for direct connection to the riser 16 as in the case of the fixture 15. In the intermediate reduced portion 30 of the section 26 there is provided a valve seat 31 located at the inner end of the inlet 32 of the structure and adapted to be engaged by the sliding valve 33, later to be described in detail, when there is no

pressure of liquid in the inlet or when a temporary vacuum has occurred in the riser 16.

The upper section 27 of the structure is provided with an internally threaded outlet 34 adapted for connection with the fixture with which the structure is associated, and said section is further provided with an externally threaded air inlet and overflow connection 35 which is in direct communication with the outlet 34 when the sliding valve 33 is in the lowered position of Figure 3, and which is shut off from said outlet by said valve when the latter is under pressure of liquid entering the inlet 32. The lower portion of the section 27, including the extension 29, is formed to provide an elongated sleeve bearing 36 in which the valve 33 is guided in its sliding movements, and surrounding said bearing are a plurality of spaced ducts 37 for establishing communication between the inlet 32 and outlet 34 so that liquid may flow from the former into the latter under ordinary operating conditions.

The sliding valve 33 is preferably of hollow tubular formation closed at its upper end 38 for engagement with the valve seat 39 of the connection 35, and open at its lower end 40 for the entrance of liquid under pressure into the sliding valve to raise the same to the position of Figure 2 and thus permit the liquid to flow through the ducts 37 into the outlet 34. Said ducts are such size and number as to allow the passage into the outlet 34 of only the required amount of liquid irrespective of the amount of pressure in the riser 16 and should there be any overflow entering the outlet 34 which will cause the valve 33 to be lowered, such overflow will then pass out through the connection 35 to the drain 24.

In the use of vacuum breakers in water distribution systems, it has been found that the efficiency of such breakers sooner or later becomes impaired due to a gradual accumulation of sediment, such as rust, about the movable parts of the breaker. As a result of such accumulation, said movable parts do not operate instantly upon occurrence of a vacuum in the supply line and under such circumstances said vacuum is likely to siphon waste water into said line before the movable valve of the breaker can properly operate. To prevent such a contingency, the valve 33 of the present invention is designed so that the

liquid entering the inlet 32, and any sediment which may be carried therewith, is diverted from the space between said valve 33 and the interior surface of the bearing 36, thus insuring against any accumulation of sediment in said space which would otherwise impair the free and proper sliding movements of the valve. Such diversion of the water and sediment is accomplished by providing the lower end portion 40 of the valve 33 with a laterally extending annular flange 41 which underlies the lower end of the bearing 36 and is provided with an upwardly beveled deflecting surface 42 against which the inflowing liquid and any sediment therein impinges so as to be deflected outwardly and thereby caused to pass through the ducts 37 instead of entering the space between the valve and its bearing.

What is claimed is:

1. In a vacuum breaker valve for use in water distribution systems, a valve body comprising separable sections one of which is provided with an inlet, an outlet and an overflow connection formed in the other section, an extension on the latter section projecting into the first named section and constituting a sleeve bearing, ducts formed in said extension for establishing communication between said inlet and outlet, and a sliding valve mounted in said bearing for controlling communication between said inlet, outlet and overflow connection, said valve having means thereon for preventing passage of sediment into the space between said bearing and valve.

2. In a vacuum breaker valve for use in water distribution systems, a valve body comprising separable sections one of which is provided with an inlet, an outlet and an overflow connection formed in the other section, an extension on the latter section projecting into the first named section and constituting a sleeve bearing, ducts formed in said extension for establishing communication between said inlet and outlet, and a sliding valve mounted in said bearing for controlling communication between said inlet, outlet and overflow connection, said valve having a flange formed with a beveled deflecting surface against which liquid entering said inlet impinges.

MODESTO CALLEJO.
